CLAIM

The ornamental design for a stirrup adjuster, as shown and described.

DESCRIPTION

FIG. 1 is a front elevational view of my stirrup adjuster showing my new design;

FIG. 2 is a side elevational view thereof, the opposite side being a mirror image of the side shown; and,

FIG. 3 is a rear elevational view thereof.

The broken lines are for purposes of illustration only and form no part of the claimed design.

FIG. 1

FIG. 2

FIG. 3
